CLAIM

I claim the ornamental design for a hay and straw compressed bale product packaging, as shown and described.

DESCRIPTION

FIG. 1 is a front and right side per perspective view of the hay and straw compressed bale product packaging;

FIG. 2 is a top plan view of the hay and straw compressed bale product packaging;

FIG. 3 is a front view of the hay and straw compressed bale product packaging;

FIG. 4 is a right side devotional view of the hay and straw compressed bale product packaging;

FIG. 5 is a rear view of the hay and straw compressed bale product packaging;

FIG. 6 is a left side elevational view of the hay and straw compressed bale product packaging; and,

FIG. 7 is a bottom view of the hay and straw compressed bale product packaging.

1 Claim, 2 Drawing Sheets
